CLAIM

The ornamental design for a set of walking poles, as shown and described.

DESCRIPTION

FIG. 1 is a right rear top perspective view of a set of walking poles;

FIG. 2 is a left front bottom perspective view of just the right pole of the set of walking poles, shown separately for ease of disclosure;

FIG. 3 is another left front bottom perspective view of just the left pole of the set of walking poles, shown separately for ease of disclosure;

FIG. 4 is a right side view of just the right pole of the set of walking poles, shown separately for ease of disclosure;

FIG. 5 is a left side view of just the right pole of the set of walking poles, shown separately for ease of disclosure;

FIG. 6 is a front view of the set of walking poles;

FIG. 7 is a rear view thereof;

FIG. 8 is a top view thereof; and,

FIG. 9 is a bottom view thereof.
